UNITED STATES PATENT OFFICE.

WILLIAM IVES, OF BUFFALO, NEW YORK.

BOOK-BRACE.

Specification forming part of Letters Patent No. 12,279, dated January 23, 1855.

To all whom it may concern:

Be it known that I, WILLIAM IVES, of Buffalo, in the county of Erie and State of New York, have invented a new and Improved Self-Supporting Book-Brace, the design of which is to confine books in an erect position on the shelves of a library or book-store, thereby giving them an orderly appearance and preventing them from falling or attaining an inclined position and consequent injury; and I do hereby declare that the following is a full and exact description of the construction and operation of the same, reference being had to the annexed drawings, making a part of this specification, in which—

Figure 1 is a perspective view; Fig. 2, the slide. Fig. 3 is a vertical transverse section of the slide, showing the pointed spring-bolt and thumb-screw. Fig. 4 is a perspective view of the bottom of the brace.

A A, Fig. 1, is the brace, in the form of a book on one side, and extending its whole length is an adjustable slide, B, which may be secured in its proper place by the thumb-screw C. To the upper end of the slide is attached a pointed spring-bolt, D. The lower end of the slot has a lateral extension or rest, E, into which the shank of the bolt may be drawn when the brace is to be placed on or taken from a shelf. To secure the foot of the brace to the shelf, there are two spurs, F F, Fig. 4.

If the brace be placed at the end of a row of books on a shelf with the slide adjusted so as to bring the shelf above within reach of the bolt, it will be seen that by detaching the shank of the bolt from the rest the shelf will be pierced by the point of the bolt, which, with the two spurs, will hold the brace firmly in its place.

The object of the slide is to make the brace available on transferring it to various shelves having spaces between them of greater or less width.

The spring-bolt may be attached directly to a brace having no slide, in which case the brace must be made in length to fit, or nearly so, a given space.

Having thus described my invention, what I claim therein as new, and desire to secure by Letters Patent, is—

1. The combining with the brace the pointed spring-bolt and spurs, substantially in the manner and for the purpose herein described.
2. The application of the adjustable slide to the brace, substantially in the manner and for the purpose herein set forth.

WILLIAM IVES.
